FACIAL MASSAGER

Martin J. Wolff, West Haven, Conn., assignor to Sperry
Rand Corporation, New York, N.Y.

Filed May 21, 1971, Ser. No. 145,995

Term of patent 14 years

Int. Cl. D24—04

U.S. Cl. D83—1

Fig. 3.

Fig. 4.

Fig. 2.

Fig. 1.

FIG. 7.

FIG. 6.

FIG. 5.

FIG. 1 is a perspective view of the facial massager, showing my new design;

FIG. 2 is a bottom plan view of the FIG. 1;

FIG. 3 is an end elevation of FIG. 1;

FIG. 4 is the other end elevation of FIG. 1;

FIG. 5 is a side elevation of FIG. 1;

FIG. 6 is a top plan view of FIG. 1; and

FIG. 7 is the other side elevation of FIG. 1.

I claim:

The ornamental design for a facial massager, as shown.
